UNITED STATES PATENT OFFICE

WILLIAM H. ROBBINS, OF SPRINGFIELD, OHIO, ASSIGNEE TO THE WILLIAMS COMPANY,
OF LONDON, OHIO, A CORPORATION OF OHIO

STEEL WOOL PAD AND HOLDER

Application filed May 23, 1927. Serial No. 193,487.

It is the object of my invention to provide a steel wool pad adapted to be used either singularly or in multiple for the purpose of being retained on a holder of various sizes and shapes.

It is a further object of my invention to provide a holder and a plurality of such pads in order to apply steel wool to varying conditions and uses.

10 Referring to the drawings:

Figure 1 is a bottom plan view of a holder having a plurality of pads.

Figure 2 is a section on the line 2—2 thereof.

15 Figure 3 is a side elevation of a power-driven holder and pads.

Figure 4 is a plan view thereof.

Figure 5 is an end elevation of another form of holder.

20 Figure 6 is a side elevation thereof.

Figure 7 is a perspective of the pad just at the completion of its winding.

Referring to the drawings, a pad is shown consisting of ribbons of steel wool designated

25 1, wound to form a flat bottom 2 and vertical side walls 3 thereof with a cup formed of strands of the wool projecting to form a steel wool fuzzy surface. This steel wool cup is mounted upon a holder consist-

30 ing of a support 4, usually a plate of wood, and to which is attached resilient felt pads 5 by the nail 6, which permits the steel wool cups to be mounted on the holder. The greater the pressure upon the holder the

35 tighter the engagement between the felt pads and the steel wool cups. In order to protect the fingers of the user, to protect the articles being treated by the steel wool and its holder and to form a further foundation for the

40 edges of the cups, I provide a border or band 7 of felt or other resilient material, which overhangs the outer edges of the tops of the steel wool cups. Such a border or band also forms a shock absorbing edge to prevent

45 wooden holder 4 from injuring the articles which are being treated by the steel wool.

A handle 8 is provided on the wooden holder itself formed into a handle 9, as in Figures 5 and 6. In Figures 3 and 4 will be

50 seen an arrangement for a power-driven

steel wool pad carrier consisting of the holder 4, a plurality of pads distributed at equidistant intervals to the power member, having a handle 10 on the motor 11 on whose armature shaft 12 the holder 4 is mounted.

By providing the plurality of such pads mounted on a plurality of retaining resilient holders I am enabled to use the wool for abrasive purposes without disintegrating into fine pieces. Hence, it has been very difficult, if not impossible, to utilize the steel wool to its full effectiveness because of its tendency to disintegrate into fine pieces of wool. By using my pad formed from a ribbon so that the cup becomes substantially an integral body, and yieldingly expanding the cup and thereby holding it together under tension by using the resilient support for the cup; and keeping the cup engaged between the surface being treated and the holder, I am enabled to use the wool to its full effectiveness. The wool being wound in continuous ribbons or strands does not disintegrate as heretofore when it is used in a bundle or a mass.

It will be understood that I desire to comprehend within my invention such modifications as within the scope of the claims may be necessary to adapt it to varying conditions and uses.

Having thus fully described my invention what I claim is new and desire to secure by Letters Patent is:

1. In combination, a holder, a resilient support projecting therefrom, and a steel wool cup consisting of concentrically wound layers of wool, said layers being formed of a plurality of individual intermingled strands of wool to form homogeneous ribbons which are found into cup form.

2. In combination, a holder, a plurality of spaced resilient projections and a plurality of cup-shaped steel wool members mounted on said projections.

3. In combination, a holder having a plurality of spaced resilient projections, a plurality of cup-shaped steel wool members mounted on said projections, and a resilient guard mounted on the edge of said holder.

4. In combination, a holder having a plu-

rality of spaced resilient projections, a plurality of cup-shaped steel wool members mounted on said projections, and a resilient guard mounted on the edge of said holder, the edge of said guard engaging portions of the top edges of said steel wool cups.

5 In testimony whereof, I affix my signature.

WILLIAM H. ROBBINS.
